DESIGN FOR A CLEARANCE LAMP OR THE LIKE FOR MOTOR VEHICLES

Henry J. Sauer, Fairfield, Conn., assignor to
The Kilborn-Sauer Company, Fairfield, Conn.,
a corporation of Connecticut

Application May 6, 1937, Serial No. 69,202

Term of patent 7 years

To all whom it may concern:

Be it known that I, Henry J. Sauer, a citizen of the United States, and a resident of Fairfield, county of Fairfield, and State of Connecticut, have invented a new, original, and ornamental Design for a Clearance Lamp or the Like for Motor Vehicles, of which the following is a specification, reference being had to the accompanying drawing, forming part thereof.

In the drawing:

Fig. 1 is a perspective view of a clearance lamp

or the like for motor vehicles, showing my new design.

Fig. 2 is a plan view.

Fig. 3 is an end view.

The dominant feature of my design resides in the parts shown in solid lines.

I claim:—

The ornamental design for a clearance lamp or the like for motor vehicles, substantially as shown and described.

HENRY J. SAUER.
